(57) **CLAIM**

The ornamental design for a portable playard for babies, as shown and described.

DESCRIPTION

FIG. 1 is a front elevational view of a portable playard for babies showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is an enlarged view of the encircled portion '9' in FIG. 7 thereof; and,

FIG. 10 is an enlarged view of the encircled portion '10' in FIG. 7 thereof.

The broken lines shown in the drawings are for the purpose of illustrating portions of the portable playard for babies and form no part of the claimed design. Additional broken lines in FIGS. 7, 9 and 10 demarcate enlarged areas and form no part of the claimed design.

1 Claim, 10 Drawing Sheets
